UNITED STATES PATENT OFFICE.

J. FORREST COBB, OF PORTLAND, OREGON, ASSIGNOR TO MOORE DRY KILN COMPANY, JACKSONVILLE, FLORIDA, A CORPORATION OF FLORIDA.

DRY KILN AND THE ART OF KILN DRYING.

Application filed September 16, 1926. Serial No. 135,891.

My invention relates to the art of kiln drying and to dry kilns of the type in which circulation of the atmosphere of a kiln is effected by the rotation of a series of power-driven rotary fans operably mounted within the kiln.

The main object of my invention is to provide a circulation within a kiln of the entire volume of the gaseous contents of the kiln, as a whole, wherein the volume of gas on one side of the drying stock is drawn through the interstices in the stock to the other side thereof, and thence back again to the side first named in constant circulation.

15 In the said course of circulation the gas is kept properly humidified and rarified to effect the best drying results.

Another object of my invention is to provide in a kiln novel means for operatively 20 mounting the fans aforesaid, wherein the result of an exceedingly stable and durable kiln structure is arrived at, with due regard to economy, and whereby the functional efficiency of the kiln, both in regard to the uniformity of the drying operation, its regulation and control, is materially enhanced.

What constitutes my invention will be hereinafter specified in detail and succinctly defined in the appended claims.

30 In the accompanying drawings, wherein my invention is illustrated in present preferred form of embodiment,

Figure I is a partial ground plan of one of my kilns taken in a plane above the floor 35 which forms the top of the fan-duct thereof, the middle portion of the kiln being broken away in order to accommodate the desired scale of the drawing, and the floor aforesaid being broken away at its opposite ends in 40 order to expose to view the heating coils that are disposed below it.

Figure II is a longitudinal vertical section of the subject matter of Figure I as shown therein, and showing also the details, 45 including the superstructure, of the kiln.

Figure III is a transverse vertical section taken on the line III—III of Figure II.

Referring to the numerals on the drawings, 1 indicates the bottom, 2 and 3 the opposite side walls, and 4 the roof of a kiln which is made, preferably throughout, of concrete construction, the bottom being made sufficiently heavy and of a proper distribution of its thickness to support the distribution of the weight it has to carry.

The roof 4 is provided at suitable intervals with damper-controlled ventilators 5, disposed in two series along the opposite sides of the roof. The opposite end openings in the kiln chamber located above the end walls 6 and 7 of the base of the kiln are closed, during the operation of the kiln, by respective doors 8, which may be, in each instance, of any preferred type that is suitable for the purpose.

A distinctive feature of my present invention is to be found in the fan-duct of the apparatus which comprises a continuous vertical wall extending substantially from end to end of the kiln, and preferably in the lower part of the kiln, in a zigzag direction, substantially as shown in plan view in Figure I. The zigzag effect of said wall is achieved by dividing the length of the kiln into medial compartments, of substantially uniform and preferred dimensions, by a series of alternately disposed substantially parallel partition walls 9 and 10, each of the walls 9 being solid, and each of the walls 10 being provided with an aperture of suitable dimensions to accommodate within it one of a series of rotary fans 11. Each pair of next adjacent walls 9 and 10 is united on one side by a solid vertical wall 12, constituting in effect a closure on one side for the compartment to which it is appropriated, the side of the compartment opposite each wall 12 being open.

The walls 12 are disposed, respectively, in succession on alternate sides of the fan-duct, so as to divide the series of compartments into units of which each alternate one is open on one side and closed on the other side. The result of the disposition just described of the several walls 9, 10 and 12 is to impart, in their assemblage, to the length of the entire wall so constituted the zigzag direction already designated.

The angle at which the walls 9 and 10 meet the walls 12, respectively, is shown in the drawings as a right angle; and that is at present deemed to be the preferable angle, but it is obvious that the angle may be varied if desired, as in some instances it may be.

Each of the walls last named is planted firmly on the bottom 1 of the kiln, with which, in the concrete construction preferred, it is incorporated. The fan-duct is completed by a floor 14 which is laid, with airtight closure, on the top of the walls 9, 10 and 12.

The floor 14 is preferably provided on opposite sides with upstanding lateral flanges 15, which, when made of concrete, is incorporated with the said floor and walls in a unitary concrete construction. The floor 14 is reinforced and supported at required intervals by cross girders 16, preferably I beams, whose opposite ends are let into and supported by the side walls 2 and 3, respectively, of the kiln.

The floor 14 carries track rails 17, and is for that reason preferably but not necessarily, particularly if but one end door is used, inclined slightly towards the outlet door 8 of the kiln, in order to utilize the force of gravity to facilitate propulsion along the track to the point of exit of trucks 18, when they are loaded with stock to be dried in the kiln. The height and width of the two corridors 19 and 20 that are defined on the outside of the fan-duct by the side walls 2 and 3 and the floor 14, respectively, should be sufficient to accommodate workmen within them with space for freedom of action as occasion may require, it being taken into account that said corridors are provided, respectively, with substantially longitudinally coextensive fresh air ducts 21 and 22 through lateral apertures 23 in which provision is made for admission in regulated quantity, of a supply of fresh, atmospheric air as often as desired, the said fresh air ducts being supplied with outside air through terminal, door-controlled, air intake openings 24.

Below the level of the bottom of the floor 14, in the respective corridors 19 and 20, are disposed heating means, preferably coils of pipe 25 and 26, arranged in any suitable and preferred system for distribution of heat, preferably steam heat that may be derived from any preferred source of steam supply, not illustrated.

A variety of steam and other heating systems being well known in the art, it is deemed unnecessary to specify more in detail the particular system illustrated, inasmuch as it constitutes, in itself, no part of my present invention.

The complement of fans 11 is driven preferably by a single shaft 27 carried in suitable aligned bearings in upright supports 28 erected on the bottom 1 of the kiln. The shaft 27 extends through the succession of walls 9 and 10 and preferably to the outside of the end wall 6, where it is operatively connected, as by a flexible coupling 29, to a motor, for example an electric motor 30, preferably located, with other incidental elements unnecessary to specify, in a housing chamber 31.

The shaft 27 may be driven in one direction only, or if provided, as it may be, with suitable reversible fans, its direction of rotation may be reversed at will, with the ef-

fect, in reversal, of the direction of circulation of the atmosphere of the kiln.

I prefer to provide each one of the series of compartments, defined, respectively, by the zigzag wall above described, with a side-wing deflecting baffle 32 (compare Figures I and III), whereby uniform direction is imparted to the currents of the circulatory medium in the kiln.

The baffles 32 are preferably located substantially in the middle of each compartment, and are, respectively, of a length equal to one half of the width of the compartment. By their disposition, the baffle is caused, in effect, to split, with increase of its efficiency, the current of the circulatory medium as discharged from each compartment. The outside wing 33 of each baffle 32 is, in effect, hinged to the baffle for control of the direction of movement, preferably by a permanent flexure, whereby the angle of each wing may be conveniently adjusted if required by application of force sufficient to bend the metal of which it is constituted.

The stock 34 to be dried in the kiln, when of lumber, is loaded in a stack or stacks upon such number of trucks 18 as may be requisite, and the method of stack piling may be of the horizontal order or of any other that may be preferred. In the drawings the stock is illustrated as horizontally piled, and in such case a fin 35, depending towards the stock pile from the middle of the roof 4 may be employed to advantage for compelling the kiln atmosphere under pressure to circulate through the horizontal spaces between the stock in the pile instead of over the top of the stack.

It is proper to add, that it is deemed unnecessary to specify all details of the heating system besides means common in the art for automatically humidifying and ventilating the atmosphere of the kiln, but that variation of said details at will are contemplated as coming within the scope of my invention.

At intervals within the kiln, I prefer to provide spray pipes 36, which may be made at will to discharge a spray as of steam, air, or even water into the atmosphere of the kiln for the purpose of properly humidifying it. A humidity-control box 37, of any well known or suitable type preferred, located in the housing chamber 31, may be used if desired.

Each of the two series of ventilators is opened at a time on one side only of the kiln, their purpose being to lead off spent or used drying medium as it accumulates in the operation of the kiln. Discharge from the open ventilators of a series is made from the side of the kiln which is opposite to the discharge side of the fan-duct.

Fresh air through the ducts 21 or 22 is introduced only on the suction side of the

fan system, which, it should be observed is, in view of the potential reversibility of the direction of rotation of the fans, a term of dual significance.

- 5 A description of the operation of my kiln, including specification of certain features of my invention, in so far as it pertains to the art of kiln drying, follows in immediate sequence.
- 10 Assuming a kiln to be built along lines in substantial conformity to those illustrated in the drawings and to be equipped with operative mechanism substantially equivalent to that illustrated, if it be assumed that the 15 kiln is supplied with material to be dried, represented by the truck load 34, that the doors (or door) 8 are closed, and that the coils 25 and 26 are heated, the drying operation is ready to start.
- 20 Thereupon the motor 30 is set in motion which is communicated to the fans 11 as by aid of the shaft 27.

Each fan, as has been specified, operates upon the gaseous contents of two contiguous compartments, upon one compartment with suction effect and upon the other with pressure effect.

- 25 Bearing in mind that the direction or rotation of the fans is reversible, and that consequently one compartment may be at one time the suction side of the fan, and that upon reversal of movement of the fan, it will be converted to the pressure side thereof, it will be understood that all the fans operate 30 in unison to effect a substantial uniformity of suction on one side of the interior of the kiln, and to exert a corresponding pneumatic pressure on the other side of the kiln. Wherefore, one side of the kiln while in operation is denominated the suction side, and the opposite side the pressure side of the kiln. The applicability of the names just indicated depends, as has just been pointed out, upon the direction of rotation of the 45 complement of fans. The pneumatic pressure generated by the fans may be by the baffle wings 33, directed towards one end or both ends of the kiln with the effect of producing circulation of the atmosphere of the 50 kiln both longitudinally and transversely in respect to the interior of the kiln, in order to satisfy the demands of the kiln conditions.

By reason of the presence of the depending fin 35 above the stock load and of the 55 lateral flanges 15 of the floor 14 below the same on the outside of the wheels of the trucks 18, the result of the coacting suction and pressure forces is, by their push and pull coaction, forcibly to drive the circulatory medium with quick, powerful and uniform drying effect through the interstices provided for circulation through the pile of stock 34.

An important feature of my invention is 60 the method by which each fan unit is pro-

vided with one inlet and one outlet of circulatory medium for each fan in whichever direction the fan revolves. It is by multiplication of said fan units that the result in kiln drying is achieved of utilizing a unified 70 drying current, with material increase in efficiency form a volume of air standpoint.

In regard to operation of the ventilators in two series, it should be considered that in the operation of any drying kiln the circulatory medium soon becomes heavily charged 75 with the liquid constituents of the drying material. The excess moisture so derived must be properly drawn off in order to maintain the efficiency of the apparatus. By providing two series of ventilators 5 and operating only one series at a time, the excess of moisture aforesaid may be kept properly drawn off. The fresh air ducts 21 and 22 contribute to the same end by substituting for 80 the spent atmosphere of the kiln that is drawn off, fresh outside air of superior drying quality. The correctness of the principle upon which the ventilators and fresh air ducts operate, respectively, is well recognized 85 in the art, but the successful application of that principle is promoted by my invention, whereby provision is made on one side of the kiln for drawing off the spent atmosphere immediately after it has passed 90 through the drying stock and becomes thereby surcharged with moisture, and then supplying fresh air from the fresh air duct which is located on the same side of the kiln as the active series of ventilators is 95 located, it being understood, of course, that when the fresh air duct 21 is open, the duct 22 is closed, and contrariwise. When the duct 21 is open, the series of ventilators on the same side of the kiln as the duct 21 is 100 open and the ventilators of the series on that side on which the duct 22 is located are closed as well as the duct.

Provision of two fresh air ducts and two corresponding series of ventilators is made 110 in order to effect the practical reversibility of the fans, already specified.

In the operations which have been described of drawing off the spent atmosphere of the kiln and the introduction of fresh air 115 in place of it, it is impracticable to measure those operations with any degree of exactitude. For that reason, in part, I employ the spray pipes 36 whose function is to provide means for maintaining the humidity of the 120 kiln atmosphere substantially at normal.

Another resultant advantage of the method of circulation accomplished by my invention is that the circulatory medium in each complete circuit is, in descending and 125 in ascending currents, respectively, twice passed through the two heating coils that are disposed, respectively, on opposite sides of the kiln.

The advantage afforded by my invention 130

of employing a unified current of the circulatory medium of a kiln is that it renders not only practicable the economical piling of stock in one comparatively compact stack without the necessity for central flues or spaces and practically without regard to the dimensions of the stack, but also actually renders such piling advantageous to the quality of the output of the kiln, in respect both to the uniformity of the drying operation, and to the economy of time required for its accomplishment.

To the accomplishment of the purpose just indicated the reversibility of the direction of circulation in the kiln is contributory, and under some conditions may be necessary.

What I claim is:

1. A dry kiln comprising within it a fan-duct defined, in part, by a continuous substantially vertical wall extending substantially the full length of the kiln in a zigzag direction.

2. A dry kiln comprising within it a fan-duct defined, in part, by a continuous substantially vertical wall extending substantially the full length of the kiln in a zigzag direction, said wall including a series of alternately disposed partition walls, of which each alternate one is solid and each alternate one is provided with an aperture for accommodation within it of a fan.

3. A dry kiln comprising a bottom, a vertical fan-duct defining wall, and a floor laid on said wall, all being of unitary concrete construction, said wall being composed of alternately disposed solid and apertured partitions united on one side thereof, respectively, to solid walls disposed successively on opposite sides of the duct, whereby a zigzag direction is imparted to the fan-duct defining wall as a whole.

4. The combination with the outside walls of a kiln of a zigzag fan-duct defining a wall extending substantially the full length of the kiln and comprising alternately disposed solid and apertured partition walls, respectively, of rotating fans operatively mounted in the apertured partition walls, respectively, and driving means in operative communication with the respective fans.

5. A dry kiln comprising within it a fan-duct defined, in part, by a continuous substantially vertical wall extending substantially the full length of the kiln in a zigzag direction, said wall including a series of alternately disposed partition walls, of which each alternate one is solid and each alternate one is provided with an aperture for accommodation within it of a fan, said fan-duct being located in the lower part of the kiln, a floor above the fan-duct, heating means located on opposite sides of a kiln, respectively, adjacent to the said floor, whereby circulation of the circulatory me-

dium of the kiln produced by rotation of the fans is caused, in passing from one side to the other of the kiln, to pass twice through said respective heating means.

6. In a dry kiln, a substantially vertical wall extending longitudinally of said kiln and having a plurality of substantially transverse partition walls, alternate partition walls having an opening, a common drive shaft extending longitudinally through all of said partition walls, and a plurality of fans mounted upon said shaft and disposed in the openings of alternate partition walls.

7. The combination with a dry kiln, of a fan unit consisting of a vertical wall extending substantially longitudinally of the kiln, substantially transverse walls associated therewith and providing a pair of communicating compartments opening toward opposite sides of the kiln, and means inducing circulation of air from one compartment to the other, one of said compartments constituting an inlet on one side of said means and the other compartment constituting an outlet on the other side of said means.

8. The combination with a dry kiln, a vertical wall arranged centrally and extending substantially longitudinally of the kiln, transverse partition walls extended from opposite sides of said vertical wall to provide a pair of compartments opening toward opposite sides of the kiln, means of communication between said compartments, and reversible means associated with said means of communication for inducing circulation of air from one compartment to the other.

9. The combination with a dry kiln, of a fan unit consisting of a vertical wall extending substantially longitudinally of the kiln, substantially transverse walls associated therewith and providing a pair of communicating compartments opening toward opposite sides of the kiln, and means inducing circulation of air from one compartment to the other, one of said compartments constituting an inlet on one side of said means and the other compartment constituting an outlet on the other side of said means, and a vertical baffle arranged substantially transversely in each compartment and terminating adjacent the middle thereof.

10. The combination with a dry kiln of a fan unit consisting of communicating compartments and an intermediate rotary fan, one of said compartments constituting an inlet on one side of the fan and the other compartment an outlet on the other side of the fan, and a baffle arranged intermediate each compartment and terminating adjacent the middle thereof.

In testimony whereof, I have hereunto set my hand.

J. FORREST COBB.
